UNITED STATES PATENT OFFICE.

GEORGE H. DENNY, OF NEWARK, NEW JERSEY.

BUNSEN BURNER FOR HEATING OR ILLUMINATING.

1,090,202.

Specification of Letters Patent. Patented Mar. 17, 1914.

Application filed September 23, 1913. Serial No. 791,307.

To all whom it may concern:

Be it known that I, GEORGE H. DENNY, a citizen of the United States, residing at 133 Third avenue, Newark, county of Essex, and 5 State of New Jersey, have invented certain new and useful Improvements in Bunsen Burners for Heating or Illuminating, fully described and represented in the following specification and the accompanying drawings, forming a part of the same.

The invention consists in a modification of the stationary tube attached to the base of the burner by which a mixing-tube is formed of sheet-metal with an integral shoulder inside such tube close to the top of the gas-regulating sleeve, so that the shoulder may operate as an air-valve-seat, and the top of the regulator-sleeve may serve as an air-valve in coöperation with such seat, to cut off 20 the supply of air in proportion as the supply of gas is increased. The shoulder is preferably formed by reverse bends in the metal to the tube which form a rounded seat for the air-valve, and the tops of the air-inlets 25 through the tube are made level with the air-valve-seat so that there is no obstruction to the passage of air thereto.

My improved construction will be understood by reference to the annexed drawing, 30 in which—

Figure 1 is an elevation of the burner; Fig. 2 a section on line 2—2 in Fig. 1 looking toward the air-valve-seat; Fig. 3 a vertical section on line 3—3 in Fig. 2; and Fig. 35 4 shows an alternative construction for the attachment, in section at the right-hand side of the center line.

A burner for an incandescent light is shown, with base *a* for connection to the gas-supply, and provided with an enlarged hub having a peripheral thread *b* to carry the yoke to support the air-valve-seat and with a smaller threaded nozzle *c* to which the regulator-sleeve *d* that carries the air-valve *e* is 40 threaded. The conical air-valve *e* has the gas-outlet hole *e'* at the center, and the nozzle *c* is provided with the needle-valve *f* to enter the gas-outlet, and has holes *c'* around the base of the needle-valve which connects 45 the gas-supply with the outlet *e'*. The mixing-tube *j* is supported upon the base *a* by columns *h* connected at the bottom to a ring *g* which is screwed to threads *b* upon the base, and at the top has a ring *i* from which 50 the metal is bent inwardly to the tube *j* to form a shoulder required for the air-valve-

seat. All these parts are of sheet-metal integral with the mixing-tube. The collar *g* and ring *i* are materially larger than the mixing-tube *j*, to form the shoulder *k* which constitutes the air-valve-seat, the sheet-metal which forms the seat being preferably bent inwardly and downwardly from the ring and then upwardly into the tube *j*, thus forming a convex seat for contact with the upper conical end of the air-valve, as is shown in Fig. 3, and producing annular channels *l* and *l'* which open downwardly and upwardly respectively. The air-valve-seat *k* is even with the lower edge of the ring *i*, so that the latter does not interfere at any time with the free access of air to the valve-seat, which is indicated by the arrows *m* in Fig. 3.

The spaces *h'* between the columns *h* permit the turning of the air-valve by the fingers, and the parts are so proportioned that when the gas-valve is gradually opened by screwing up the regulator, the air-valve contracts the air-passage between itself and the seat *k* and thus diminishes the supply of air in proportion as the supply of gas is increased; until the full supply of gas is permitted and the air is entirely cut off by the contact of the air-valve with the seat *k*.

The valve-seat may, if desired, be connected with the columns by a flat flange *n*, and all formed of sheet-metal as shown in Fig. 4, but this construction does not present the same visible features at the top and bottom of the columns, as the latter must be extended all the way to such flange to avoid interference with the movement of the air from the spaces *h'* to the valve-seat. The collar *g*, the columns *h* and the ring *i* are 95 preferably of the same cylindrical dimensions, which greatly facilitates the manufacture of this attachment in the drawing or stamping of the sheet-metal to form these parts.

In my construction, the regulator *d* without any extraneous attachments performs the desired function of varying the flow of the air and gas inversely, thus greatly simplifying and cheapening the construction.

Bunsen burners having the same general features as mine are already known, but not possessing a mixing-tube of sheet-metal formed in one piece with a shoulder by expanding the tube at a suitable point, and extending such expanded portion downward in the form of legs to an integral collar by

which the legs can be connected to the base of the burner. By my construction, the burner-base requires an enlarged hub considerably larger than the mixing-tube, to receive the collar *g* which is formed by expanding the lower part of such mixing-tube; and the use of a casting to form the valve-seat and support the mixing-tube upon the base is wholly avoided. My invention therefore includes such an integral construction of sheet-metal as just described, and also the particular construction of the air-valve-seat by forming annular channels *l, l'*, between the valve-seat and the ring *i* so as to produce a smooth rounded air-valve-seat over which the air can flow freely from the spaces *h*.

Having thus set forth the nature of the invention what is claimed herein is:

1. In a gas-burner, the combination, with a base having a threaded nozzle with a needle-valve thereon, of a combined gas-regulator and air-valve threaded upon the nozzle, a sheet-metal mixing-tube having a shoulder forming an integral convex air-valve-seat adjacent to the top of the air-valve, the metal of such seat being expanded

into a ring materially larger than the mixing-tube, with columns extended downward from such ring, and a collar at the bottom 30 of the columns secured upon the base, such valve-seat, expanded ring and columns being of sheet-metal integral with the mixing-tube, as and for the purpose set forth.

2. In a gas-burner, the combination, with 35 a base having a threaded nozzle with a needle-valve thereon, of a combined gas-regulator and air-valve threaded upon the nozzle, a sheet-metal mixing-tube having a shoulder forming an integral convex air- 40 valve-seat adjacent to the top of the air-valve with the sheet-metal bent upwardly therefrom and outwardly and downwardly into a ring level with the said convex seat, and columns extended downwardly from the 45 ring and secured upon the base.

In testimony whereof I have hereunto set my hand in the presence of two subscribing witnesses.

GEORGE H. DENNY.
